UNITED STATES PATENT OFFICE.

ALBERT B. SHULTZ, OF BUFFALO, NEW YORK.

GAS-ENGINE BODY OR FRAME.

1,226,820.

Specification of Letters Patent. Patented May 22, 1917.

Application filed February 26, 1915. Serial No. 10,659.

To all whom it may concern:

Be it known that I, ALBERT B. SHULTZ, a citizen of the United States, residing at Buffalo, in the county of Erie and State of New York, have invented new and useful Improvements in Gas-Engine Bodies or Frames, of which the following is a specification.

This invention relates to gas engines and more particularly to such engines in which the body or frame comprises upper and lower base sections which are detachably connected with each other and one or more cylinders which are detachably mounted on the upper base section. In this type of gas engines which are used more particularly for motor boats and the like a plurality of cylinders are usually arranged in a longitudinal row so that the base is liable to bend, spring or sag under the weight imposed upon the same and not only interfere with the free rotation of the main shaft which is mounted on the base but also cause displacement of other parts of the engine, and thereby reduce its efficiency and also render the same liable to break.

In the bodies of gas engines of this type as heretofore constructed the cylinders were also usually connected with the base by means of screws having their heads arranged outside of the cylinders and passing through external annular flanges on the cylinders which construction is objectionable for the reason that these flanges are liable to be broken off and are also unsightly on the outer side of the body and difficult to keep clean.

It is one of the objects of this invention to so design the upper section of the base upon which the crank shaft is mounted that the opposite longitudinal edges of the same which rest upon the lower base section are arranged at a point below the axis of the crank shaft bearings, whereby an arch or truss is formed transversely of the upper base section which effectually braces or strengthens this base section and also resists any tendency of the crank shaft bearings to sag out of their normal position.

Another object of this invention is to so construct the lower edge portions of the upper base section that the same are materially strengthened without causing any parts of such strengthening means to project beyond the outer side of this section and also to arrange the connections between the

upper and lower base sections within the upper base section, thereby not only improving the appearance of the same but also avoiding external obstructions which otherwise would render it difficult to keep the engine clean.

A further object of this invention is to so connect the cylinders of the body with the base thereof that the fastening means are arranged within the base and concealed from view and the use of external connecting flanges is avoided and instead the lower ends of the water jacket are utilized to receive the fastening bolts so that these water jackets serve the added purpose of connecting opposite ends of the cylinders and thus strengthening the same in a direction lengthwise of their axes.

In the accompanying drawings: Figure 1 is a vertical transverse section of a gas engine body embodying my improvements, the section being taken through one of the cylinders. Fig. 2 is a fragmentary longitudinal section thereof taken through the cylinders and the crank shaft bearings.

Similar characters of reference indicate corresponding parts in both figures.

In its general organization the engine body containing my improvements comprises a lower base section 1, an upper base section 2 and a cylinder section 3. The lower base section has its central part dished downwardly so as to form a pan or basin 4 and at its opposite longitudinal edges this pan is provided with outwardly projecting flanges 5 the upper sides of which are preferably provided with channels or grooves 6 adapted to receive the oil which drips downwardly from the upper external surfaces of the engine.

The upper base section comprises two longitudinal side walls or sides 7, 8 which preferably diverge downwardly and rest at their lower edges upon the longitudinal edges or flanges of the lower base section, these walls being provided at suitable places with hand holes 8 which are normally closed by covers 9 secured thereto by means of screws 10, as shown, or other suitable means. The upper base section is preferably detachably connected with the lower base section by means of upright screws 11 arranged adjacent to the inner side of the longitudinal walls of the upper base section and passing through projections 12 arranged on the inner side of the lower base

section adjacent to opposite longitudinal edges thereof, whereby these fastening means are concealed from view and not only improve the appearance of the engine but 5 also render it possible to keep the engine clean more easily. These projections 12 are preferably constructed in the form of channels extending lengthwise of the upper base section, as shown in the drawings, so that 10 they also serve to materially strengthen the same without any increase in weight.

At suitable intervals and adjacent to their opposite ends the longitudinal walls of the upper base section are connected by trans- 15 verse webs 13 which extend substantially the entire height of these sides or walls and each of which is provided at its lower edge and midway between the longitudinal walls of the upper base section with a segmental 20 crank shaft bearing forming part of a complete bearing 14 in which the main or crank shaft 15 of the engine is journaled. Heretofore the axes of the several bearings of the upper base section have been arranged horizontally in line with the joint between the 25 upper and lower base sections which construction in the case of a very long engine base having a large number of cylinders is objectionable for the reason that the base is liable to spring or bend under the weight 30 imposed upon the same and permit the crank shaft bearings to sag to such an extent that this shaft would be displaced and not only bind in its bearings but also become 35 cramped with reference to other parts associated therewith and therefore not only work improperly but also impair the efficiency or output of the engine as well as increase the upkeep of the same. To avoid such sagging 40 of the crank shaft bearings the same are so arranged on the webs of the upper base section that the lower edges of the walls of this section are arranged below the axes of the crank shaft bearings, as shown in Fig. 1, in 45 other words, the joint between the upper and lower base sections is below the axes of the crank shaft bearings. By thus arranging the axes of the crank shaft bearings above the lower edges of the longitudinal 50 walls of the lower base section, a plurality of transverse arches or trusses is produced which not only materially strengthens or stiffens the same as a whole but also prevents the crank shaft bearings from sagging 55 so that displacement of the crank shaft is positively prevented. This arching or bracing effect of the upper base section is further increased by reason of the downwardly diverging arrangement of the longitudinal 60 walls thereof, so that taken as a whole the several planes of the main surfaces of the upper base section are so arranged that no two of these planes are arranged parallel with each other, this being due to the fact 65 that the upper side or surface of the upper

base section is horizontal, the lower side thereof consists of two surface sections which diverge or slant downwardly from the crank shaft bearings to the longitudinal lower edges of the side walls, and the side 70 walls diverge or slant downwardly from the top of the upper base section toward the bottom thereof, as clearly shown in Fig. 1.

Furthermore by so constructing the supports for the crank shaft bearings so that 75 the undersides of these supports diverge from the bearings downwardly to the resting edges of the upper base section greater clearance space is provided within the base in order to permit an attendant to readily 80 gain access to these bearings for inspection, adjustment and repairs of the same and other parts within the base.

Each of the cylinders 16 of the cylinder section projects with its lower end downwardly through an opening in the top of the upper base section and is provided with a downwardly facing shoulder 17 which rests upon the upper edges of the longitudinal walls and the adjacent transverse webs. 85 Surrounding each of the cylinders is a water jacket or shell 18 which is separated from the latter so as to form an intervening water space 19 but is connected at its upper and lower ends with the corresponding upper and lower ends of the respective cylinder. At its lower end each of the water jackets or shells is thickened as shown at 20 and provided with downwardly opening screw threaded sockets 21. The latter are 90 adapted to receive the upper ends of fastening screws 22 which pass through internal lugs 23 at the upper edges of the longitudinal walls of the upper base section and have 95 their heads bearing against the underside of said lugs. By this means the fastenings which connect the cylinder sections with the upper base section are concealed from view and externally projecting bolts are avoided, 100 whereby the engine is not only improved in 105 appearance but cleaning of the same is also more convenient.

Furthermore, by connecting the lower ends of the water jackets directly with the upper base section these jackets serve as a 110 tie between the upper and lower ends of the cylinder and aid in materially strengthening the latter.

From the foregoing it will be clearly apparent that by extending the longitudinal walls of the upper base section downwardly below the axes of the crank shaft bearings an increased vertical section of metal is obtained in the webs and longitudinal walls of this section which is so distributed that a 115 much stronger and rigid structure is produced, the jackets of the cylinders which have heretofore been used solely for cooling purposes are now also utilized to double the tie between the ends of the cylinders and 120 125 130

increase the durability of the engine as a whole, and by concealing within the base the fastenings which connect the upper base section with the lower base section and cylinder section, a smooth and finished external appearance of the engine body is produced.

5 No claim is made in the present case for the means whereby the upper base section is secured to the lower base section and to 10 the cylinder, these features forming the subject of a separate application for patent which was filed October 29, 1915, Serial No. 58,577.

If desired the lower base section may be 15 dispensed with in which case the upper section alone serves as the body and rests at its lower edges on a suitable support.

I claim as my invention:

1. A body for gas engines comprising a 20 lower base section, and an upper base section having two longitudinal walls, the lower edges of which are secured to the

lower base section and also having supports which are provided with crank shaft bearings and which diverge on their under sides from said bearings downwardly to the edges 25 of said upper base section, the joint between said upper and lower base sections being arranged below the axes of said crank shaft bearings.

2. A crank case, comprising a body portion including sides and webs adjacent the opposite ends of said sides extending substantially the entire height of said sides and having segmental crank shaft bearings 35 formed in their bottom faces, said bottom faces slanting downwardly from said bearings to said sides.

Witness my hand this 24th day of February, 1915.

ALBERT B. SHULTZ.
